UNITED STATES PATENT OFFICE.

HARRY J. BURTIS, OF LAWRENCE, KANSAS.

COMPUTING-MACHINE.

No. 890,600.

Specification of Letters Patent. Patented June 18, 1908.

Application filed February 4, 1907. Serial No. 355,673.

To all whom it may concern:

Be it known that I, HARRY J. BURTIS, citizen of the United States, residing at Lawrence, in the county of Douglas and State of 5 Kansas, have invented certain new and useful Improvements in Computing-Machines, of which the following is a specification.

My invention relates to computing devices and has special reference to mechanism adapted to register the results obtained in the processes of adding and subtracting numbers arithmetically.

The chief objects of my improvement are to devise a simple, compact and accurate 15 mechanism for the purpose stated; to produce a combined adding and subtracting machine the operation of which will be simple and readily understood and which can thus be used by an unskilled person; to design 20 an apparatus for registering results in arithmetical problems, having few parts and that in consequence can be economically manufactured and will not be liable to get out of order.

25 My device comprises, generally speaking, a casing upon the upper surface of which is imprinted series of columns of figures which constitute the key board, a number of registering wheels, actuating devices consisting 30 of bands or belts arranged in parallel, means for operating the bands, and mechanism for carrying to, or deducting from, a higher denomination.

In the accompanying drawing which forms 35 a part of this specification for patent, I have shown my improved combined adding and subtracting machine in the following views:—

Figure 1 is a top plan view of the complete device, a portion of the casing having been 40 broken away and some parts removed in order to disclose the internal mechanism; Fig. 2 is a sectional view taken on the line 2—2 of Fig. 1; Fig. 3 is a fragmentary view, partly in section to illustrate the method of 45 carrying and deducting; Fig. 4 is a view of the right hand side of one of the registering wheels showing one of the transfer pinions in engagement therewith, and Fig. 5 is a view of the left hand side of another registering 50 wheel also showing one of the pinions in its relation to the gear teeth.

Referring to the drawing in detail, 6 indicates the base plate, 7 the sides, 8 and 9 the front and rear ends, respectively, and 10 the 55 cover of a casing within which is located the mechanism. The cover is hinged at 11 to

the rear plate 9 and is inclined downward from the rear towards the front of the casing where it is furnished with a handle or knob 12, by means of which the cover may be lifted 60 on its hinges to permit of ready access to the working parts. The said cover is provided with a series of parallel longitudinal slots 13 which extend approximately the length of the cover, and upon either side of each slot 65 and parallel therewith are arranged columns of characters 14, comprising the figures from 0 to 9 inclusive. The figures are spaced equally apart longitudinally in the column and those upon one side, preferably the right, 70 are arranged in numerical order from above downward, beginning near the top with 0 and increasing downward by increments of 1 until the digit 9 is reached. This right hand column is used in problems requiring addition and is designated for convenience by a plus sign 15, placed at the top of the column. The column of symbols placed upon the left hand side of each slot likewise comprise the figures from 0 to 9 as previously stated, but 75 arranged in reverse order, beginning with the character 0 at the bottom of the column, directly opposite the figure 9 of the plus column and increasing upward by increments of 1 until 9 is reached which coincides 80 with the character 0 in the opposite column 15. The said left hand column is employed in arithmetical computations embracing subtraction and for this reason is designated by the minus sign 16, placed at the head of the 85 column as in the case of those used for addition.

Near either end of the casing and extending transversely between the side plates 7 are fixed rods 17, 18, secured to the casing by 90 bearing plates 19. The rear rod 17 carries registering wheels 20, arranged at intervals corresponding with the spacing of the slots 13 in the cover 10. The said wheels are maintained at their proper locations by sleeves 21 100 which engage the hubs 22 of the wheels 20 to prevent lateral displacement but permit them to rotate freely when actuated in the manner hereinafter set forth. The rims 23 of the said wheels are reduced in diameter 105 for approximately half their width to form a sprocket 24 provided with teeth 25, ten in number which are arranged at equal intervals on the face of the sprocket. The face 26 of the raised portion of the rim 23 has 110 impressed thereon at regular intervals by stamping, or otherwise, the numerical char-

acters 0 to 9, indicated on the drawing by 27. The registering wheels are located so that their faces are in close proximity to the cover of the casing and said cover is provided with 5 sight apertures 27^a through which a single character on said face of each wheel will be exposed to view when opposite the opening. Each rim is provided upon one side with an internal gear 28, furnished with any number 10 of teeth divisible by ten. I prefer, however, to construct these gears with one hundred teeth each, so that ten teeth will correspond with each numerical division of the face of the wheel. Upon the opposite side of each 15 registering wheel is a mutilated gear comprising a segment 29 having a less number of teeth than the number in the internal gear 28 corresponding with the said numerical division. In this instance, the said segment 20 gear 29 is provided with eight teeth. I have shown four registering wheels assembled upon the rod and four slots 13 formed in the cover. It is evident, however, that any number desired of such wheels may be arranged 25 in series upon the rod 17, and corresponding slots be provided in the casing by increasing the lateral dimension, and I do not wish therefore to be limited to the precise number of registering elements illustrated. 30 The registering wheels thus disposed are considered to bear denominations corresponding with their relative positions, the first wheel upon the right hand being considered as units, the next to the left as tens and so on, 35 in the manner well known in the art.

In order to provide means for actuating the registering wheels, I provide endless bands or belts 30 which pass over the sprockets 24, the teeth 25 engaging apertures 31 40 in said bands. Midway between said apertures, the spaces between which correspond with the numerical intervals of the rims 23, and necessarily also the spaces between the sprocket teeth, are located operating pins 32, 45 which are secured to the bands 30, in any convenient manner, and project through the corresponding slot to a sufficient extent to be readily grasped by the fingers. The said bands are kept taut by means of grooved 50 pulleys or idlers 33, which are journaled on the said rod 18 near the front of the casing, and kept from lateral displacement by sleeves 34, pinned or otherwise secured to the rod. It will be understood that the inter- 55 vals between said operating pins not only correspond with the numerical intervals upon the face of the registering wheels, but also with the columnar division shown on the face of the cover, which face may properly be 60 designated the key board.

As in all numerical registering devices, provision must be made for transferring the movement of each wheel to one of a higher 65 denomination during some period of the rotation of the former, so as to turn said wheel of

higher denomination one step forward or backward according to the character of the operation being performed. I accomplish the desired result in the following manner: In the interval between each adjacent pair of 70 registering wheels is mounted a short shaft or arbor 35 journaled in a bearing 36 secured to the base plate by screws 37. Upon the ends of this arbor 35 and mounted or cut integral therewith are transfer pinions 38, 39, 75 which mesh with the gears carried by the registering wheels. The pinion 38 has ten teeth and engages the gear 28 having one hundred teeth, being constantly in mesh therewith. The opposite pinion 39 has teeth 80 which correspond in pitch with the segment gear 29. The peripheral location of the said gear 29 bears such a relation to the character 0 of its registering wheel that when this figure passes the sight aperture 27^a the segment 29 will engage the pinion 39 and turn it one revolution, and as the relation which the pinion 38 upon the other end of the arbor bears to the gear 28 is 1 to 10, the registering 85 wheel corresponding to that individual gear 90 will be given one tenth of a revolution, thus bringing another figure before the corresponding sight aperture.

To explain the method of using the apparatus to register the totals of arithmetical 95 additions and subtractions, I will first describe its application for addition: Supposing all the registering wheels to be arranged so that 0 shows opposite each sight aperture, and it is desired to add the numbers 97 and 3, 100 the operator grasps the pin which projects through the tens slot, which is the second from the right and is opposite the 0 in the right hand or plus column, and moves it downward until said pin is directly opposite 105 the digit 9 in the same column, which was the numeral to be added. This movement of the band by means of the pin will turn the corresponding registering wheel nine tenths of a revolution and bring the figure 9 on its 110 face opposite the sight opening. Releasing the pin in the tens column the operator will then grasp the pin in the units slot opposite the 0 of the plus column and move it downward as before until it is opposite the digit to 115 be added, which is 7. The units wheel will now register 7 in its sight opening. To complete the computation by the addition of 3 the operator takes hold of the pin in the units column opposite the right hand 0, as before 120 and moves it downward until opposite 3 in that column. The units wheel will now show 0 and the tens wheel will have been moved one step by the action of the transfer gears and the hundreds wheel will also have 125 been moved one division and the digit 1 will appear before the aperture; thus the device will register 100.

It will be seen that in the process of addition the pin opposite the 0 in the right hand 130

- column is always the one to be grasped and is to be moved downward until opposite that figure in the column which it is desired to add.
- 5 In subtraction the result is reached by a reversal of the operation for adding except that the left hand column is the one used as the indicator. Thus the operator grasps the pin opposite the 0 in the left hand column 10 and moves it upward until it is directly opposite the figure which it is desired to subtract from that column thus reversing the rotary movement of the registering wheels. The action of the segment gear will be to 15 turn the wheel of the next higher denomination one step backward as it passes the transfer pinion thus deducting one unit on that wheel at each reverse revolution of the operated wheel.
- 20 It is obvious that minor changes may be made in the mechanical parts of my device as herein disclosed without departing from the scope and spirit of my invention and I do not wish, therefore, to be limited to the precise details of construction set forth.
- Having thus described my invention what I claim is:—
1. In a computing device, the combination with a casing provided with a plurality of 30 parallel slots, and furnished with indicating characters arranged adjacent to said slots, of a series of registering elements, each element consisting of a rim having a reduced portion, a hub connected to the rim by a web formed integral with both rim and hub, an internal gear carried on one rim upon one side and a segmental gear carried upon the opposite side of each element, means for transferring the movement of each registering element to the 35 next higher denomination, and endless metal bands traveling around said reduced portions of the registering elements, spaced pins attached to said endless bands and projecting through said slots in the casing.
- 40 2. A computing device, including a series of registering elements, each element composed of a rim, a hub connected to the rim by a web, an internal gear carried by the rim, endless metal bands traveling around said 45 rim, spaced pins attached to said endless bands, transfer shafts arranged between adjacent registering elements, pinions mounted upon each of said shafts, one pinion engaging the internal gear of a registering element and the other pinion adapted to be 50 engaged by the element of next lower denomination, a casing plate provided with longitudinal parallel slots, and indicating characters arranged adjacent to said slots.
- 55 3. In a computing machine the combination with the casing, of a number of wheels 60 each wheel composed of a rim having a portion reduced in diameter and provided with sprockets, a web connecting the rim and hub and formed integral therewith, an internal gear formed upon one margin of said rim, an incomplete internal gear carried upon the other margin of the rim, a transfer element adapted to engage the gears of adjacent wheels, a series of bands engaging the reduced portions of said number of wheels and spaced pins attached to said bands and projecting through slots in said casing.
4. In a computing device, the combination with the casing of a series of registering elements composed of a rim having a reduced portion, a hub, a web connecting said hub and rim and joined integrally therewith, a complete internal gear formed in one margin of said rim and an incomplete internal gear 70 formed in the other margin of said rim, a series of endless flat metallic bands traveling around and operatively engaging the faces of the reduced portions of the rims, transfer shafts journaled in posts located between adjacent registering elements, a pinion mounted upon one end of said shaft and engaging the complete gear of one element, a toothed wheel carried upon the other end of the shaft and adapted to be engaged by the incomplete 75 gear of another element, and a casing plate provided with longitudinal parallel slots and figures arranged adjacent to said slots.
5. In a computing machine, the combination with the casing, of a series of registering elements composed of a rim having a reduced portion, a hub, a web connecting said hub and rim, said hub, web and rim being formed integrally, a complete internal gear formed 80 in one margin of said rim, a series of endless flat metallic bands traveling around and operatively engaging the faces of the reduced portions of the rims, transfer shafts journaled in supports located between adjacent 85 registering elements, a pinion mounted upon one end of each shaft and engaging the complete gear of one element, a toothed wheel carried upon the other end of the shaft and adapted to be engaged by the element of 90 lower denomination, a series of grooved idlers adapted to be engaged by said endless bands, and a casing plate provided with longitudinal parallel slots and furnished with columns of figures arranged upon opposite sides of said 95 slots.
- In testimony whereof I affix my signature in presence of two witnesses.
